UNITED STATES PATENT OFFICE.

HORACE H. PEEK, OF CHATTANOOGA, TENNESSEE.

FURNACE.

1,400,454.

Specification of Letters Patent. Patented Dec. 13, 1921.

Application filed April 12, 1920. Serial No. 373,447.

To all whom it may concern:

Be it known that I, HORACE H. PEEK, a citizen of the United States of America, residing at Chattanooga, in the county of 5 Hamilton and State of Tennessee, have invented new and useful Improvements in Furnaces, of which the following is a specification.

This invention relates to furnace constructions, and has for an object the provision of a down draft furnace, which is especially designed as a pipe heating furnace, although it will be apparent that it may be used for heating material or objects of any 15 character.

Another object of the invention is the provision of a furnace in which the heat units are evenly distributed to all parts of the heating chamber or oven, so as to uniformly 20 heat the contents thereof, this result being accomplished by novel arrangement of gas and fresh air distributing passages, the latter mixing with the products of combustion at the top of the bridge wall, to aid in the 25 combustion of fine particles of fuel.

Another object is the provision of a furnace in which the hot gases are taken out upon each side of the hearth through a plurality of passages, thereby insuring an even 30 distribution throughout the oven.

A further object is the provision of a plurality of separate damper controlled draft passages, with which the gas distributing passages communicate, the draft passages 35 regulating through their dampers, the amount of draft or suction from each end of the draft passage, so that the products of combustion may be drawn through the oven and distributed over the oven's contents at 40 the proper degree.

Other objects and advantages of the invention will appear as the following description is read in connection with the accompanying drawings,

45 In the drawings:

Figure 1 is a vertical sectional view through a furnace embodying the present invention, the section being taken on the line 1-1 of Fig. 2.

50 Fig. 2 is a horizontal sectional view on the line 2-2 of Fig. 1.

Fig. 3 is a vertical section on the line 3-3 of Fig. 2.

55 Fig. 4 is a horizontal section on the line 4-4 of Fig. 1.

Referring specifically to the drawings,

wherein like characters of reference denote corresponding parts, the furnace comprises an outer casing, which is preferably formed of sheet steel and indicated at 10, an inner 60 lining 11 of asbestos, a second lining 12 of red brick, within which is placed an additional lining of firebrick 13. While this provides a very effective construction of heat insulating wall, it is not the purpose of the 65 present application to be confined to this particular structure, which may be varied as desired.

Located in one end of the furnace is a pair of fire boxes 14, to which access is attained 70 through feed doors 15 located upon opposite sides of the furnace, the fire boxes being separated by a wall 16. Beneath the fireboxes and separated therefrom by a grate 17 is an ash pit 18, which may extend the 75 entire width of the furnace beneath both fire boxes and be provided with a door at each end.

Also located within the furnace is a heating chamber or oven 19, the latter being 80 separated from the fire boxes 17 by means of a bridge wall 20. The oven 19 extends the entire width of the furnace and is provided at one end with a charging door 21 and at its opposite end with a discharging 85 door 22. Extending over the tops of both fire boxes 17 and the oven 19, is a crown or dome 23, the curvature of which directs the products of combustion which rise from the fire boxes 17, across the bridge wall and 90 downward into the heating chamber or oven 19.

For the purpose of supplying fresh air to the interior of the furnace for mixture with the gases, and to aid in consuming the fine 95 particles of fuel, there is provided beneath the oven extending transversely of the furnace, a fresh air inlet 24. This fresh air inlet is in the form of a passage open at each end and communicating with this passage is a plurality of spaced passages 25, both the passages 24 and 25 being horizontally arranged. Each of the last mentioned passages is provided with oppositely and inwardly extending passages 26, which meet 100 and communicate with vertical passages 27 extending upwardly through the bridge wall 20 and opening at the top thereof. The fresh air is thus delivered to the hot gases as they rise from the fire box and between 105 the said fire box and the oven.

Extending from the opposite sides of the

oven 19 is a number of horizontally alined openings 28, these openings being arranged an appreciable distance below the top of the walls of the oven, and communicating with vertically arranged passages 29. The passages 29 extend downwardly and at their bottoms communicate with horizontally arranged draft passages 30, the passages 29 being arranged oppositely and in pairs and 10 each pair being in communication with an individual draft passage. The passages 30 have one end open to the atmosphere as indicated at 31 and have their opposite ends in communication with the flue 32, so that a 15 draft is established through the passages 30, which will suck the gases through the passages 29 at each side of the oven 19. Each draft passage 30 is provided with a damper 33 for controlling the draft and by manipulating each of the dampers, the distribution 20 of heat through the oven may be regulated.

The invention is susceptible of various changes in its form, proportions and minor details of construction, and the right is herein reserved to make such changes as properly fall within the scope of the appended 25 claims.

Having described the invention what is claimed is:—

- 30 1. A furnace comprising a casing, a heating chamber or oven located therein, a fire box located at one side of the oven and separated therefrom by a bridge wall, a crown wall or dome covering the oven and fire box for directing the products of combustion from the latter across the bridge wall into the former, fresh air passages opening through the top of the bridge wall and a plurality of passages connecting with the oven through the side walls in a plane below the fresh air inlets for conducting the gases to the atmosphere.
- 40 2. A furnace comprising a casing, a heat-

ing chamber or oven located therein, a fire box located at one side of the oven and 45 separated therefrom by a bridge wall, a crown wall or dome covering the oven and fire box for directing the products of combustion from the latter across the bridge wall, spaced vertical draft passages arranged upon opposite sides of and communicating with the oven through said walls at a point below the top thereof, longitudinal passages extending between the oven and establishing communication between the vertical gas passages and the atmosphere and fresh air passages extending through the bridge wall and opening through the top of the latter for mixing fresh air with the products of combustion.

3. A furnace comprising a fire box, a heating chamber or oven, means for directing the products of combustion from the fire box into the top of the oven, air passages for directing a supply of fresh air into the path of the products of combustion before they enter the oven, a plurality of gas passages leading from the oven and separate damper controlled passages communicating with the gas passages and open at both ends to the 70 atmosphere.

4. A furnace comprising a casing, a heating chamber located therein, a fire box located at one side of said chamber and separated therefrom by a bridge wall, a crown wall covering the chamber and fire box for directing the products of combustion from the latter across the bridge wall into the former, fresh air passages entering through the top of the bridge wall and a plurality of damper controlled passages horizontally arranged beneath said fresh air inlets and curved at one end for conducting the gases to the atmosphere.

In testimony whereof I affix my signature. 85
HORACE H. PEEK.
